United States Patent Office

Des. 187,644

Patented Apr. 12, 1960

187,644

TILE

William A. Neumann, South Euclid, Ohio, assignor to Summitville Tiles, Inc., Summitville, Ohio, a corporation of Ohio

Application May 1, 1959, Serial No. 55,741

Term of patent 14 years

(Cl. D18—2)

Fig. 1 is a front perspective view of a tile, showing my new design.

Fig. 2 is a cross sectional view taken substantially as indicated on line 2—2 in Fig. 1.

I claim:

The ornamental design for a tile, substantially as shown.
